UNITED STATES PATENT OFFICE

CLAUDE SIEBRING, OF GEORGE, IOWA

BROODER

Application filed May 18, 1928. Serial No. 278,855.

My invention relates to brooders and has for its object to provide a heating unit for a brooder, having novel and improved features of construction.

5 Another object of my invention is to provide a combined heating unit and forced draft ventilating system for the brooder.

The stove of my invention is one which may be converted to the type commonly 10 known as the "drip feed", wherein the fuel is allowed to drip from a height through a vertical pipe which comprises the air inlet onto a vaporizing device, from whence the draft carries it in a horizontal plane through 15 a twisting passageway, in which it is burned.

Another object of my invention is to provide a heating unit for a brooder, which combines, with the advantages of the winding passageway type of oil burning stove, the 20 utmost simplicity, durability and cheapness of construction.

More specifically referring to the last object, it is my intention to construct a stove of the type mentioned entirely of pipe or 25 tubing, which may be of the same diameter throughout.

Another object is to provide with such a stove simple and novel means for supporting the stove, said means being adjustable as to 30 height.

Another object is to provide a combined heating unit and forced draft ventilator, together with simple and novel means for controlling the draft to the ventilator.

35 Another object is to provide novel means for supporting a fuel tank upon the upper end of the feed tube of the stove.

With these and other objects in view, my invention consists in the construction, arrangement and combination of the various 40 parts of my device, whereby the objects contemplated are attained, as hereinafter more fully set forth, pointed out in my claims, and illustrated in the accompanying drawings, in 45 which:

Fig. 1 is a sectional view taken through the center of a brooder involving my invention.

50 Fig. 2 is a plan view of the stove detached from the brooder.

Fig. 3 is a perspective view of one of the supporting legs of the stove.

Fig. 4 is an enlarged, detail, sectional view through the lower portion of the air inlet flue of the stove.

55 Fig. 5 is a sectional view through the upper end of the air inlet flue illustrating the fuel tank which is employed when the drip system is used.

In Fig. 1, I have illustrated a conventional 60 form of brooder having the side walls 10 and the roof 11 and having at its top a ventilator 12.

Ordinarily the air from the brooder simply passes through an opening in the roof 65 below the ventilator and thence into the atmosphere.

My invention aims to utilize the stack 13 of the brooder stove for the purpose of creating a forced draft to the ventilator 12.

70 To this end, the stack 13 is surrounded by a sleeve 14, concentrically spaced from the flue 13 and suitably supported in the ventilation opening in the roof 11. The ventilator 12 is supported by means of arms 15 upon 75 the upper end of the sleeve 14.

The stack 13 might be formed as an integral continuation of the chimney 16 of the stove, or it may be constructed separately and fitted thereover, as shown in Fig. 1. 80 Upon the chimney 16 is slidably supported a damper 17, which, when raised to the level of the lower end of the sleeve 14, will completely shut off circulation of air therethrough and which will vary the draft 85 through the sleeve in proportion to its height. A set screw or the like 18 may be used for securing the damper 17 in any of its adjusted positions. As will be evident from the drawings, the damper 17 comprises a circular plate having an integral collar snugly fitting over the chimney 16.

90 The stove comprises the chimney 16, which is vertical, the vertical inlet flue 19, and a winding passageway positioned in a horizontal plane and comprising the sections 20, 21, 22, 23, and 24, joined together to form an S shaped construction, the ends of which are joined respectively to the chimney 16 and the inlet flue 19.

A diagonal brace 25 connects the pipes 16 and 19 and forms a rigid structure of the winding series of pipes.

There are several advantages in the construction just described over the old type of construction of drip feed burner, (which comprised a rectangular box, partitioned off to form a winding passage), one of these advantages being the simplicity of construction which is obtained by the use of uniform pipe sections joined together to form the winding passageway. Another advantage resides in a marked increase in heat radiation in the present construction as compared with the closed box-like structure of prior devices.

Another advantage in the present construction resides in the possibility of attachment to the vertical pipes 16 and 19 of a pair of supporting legs, which may be adjusted relative to those pipes, without interfering with the intervening passageway portion of the stove. By slidingly attaching the legs directly to the pipes 16 and 19, a vertically adjustable supporting structure of the utmost simplicity may be obtained.

The desirability of vertical adjustment of the stove has been recognized prior to my invention. The advantage of the feature resides in the ability to adjust the intensity of heat radiation from the stove to the chicks below the stove.

In this respect, it will be understood that in the most approved forms of chick hovers, not only the hover, but the stove itself should be preferably adjustable as to height from the floor of the brooder.

The supporting structure comprises two independent legs, each having a channel shaped base 26, a pair of uprights 27 and 28, connected at their lower ends to the base 26 and secured at their upper ends to a split ring 29, adapted to encircle and clamp each of the upright pipes 16 and 19. A tightening bolt 30, which may be a thumb nut or the like, clamps the ring 29 against its respective pipe.

It will now be noted that the pipes 16 and 19, respectively, are received between the uprights 27 and 28, and that the stove may be lowered until the horizontal pipes 20 and 24 rest upon the upper edges of the channels 26. Thus at no time will the stove be allowed to come into contact with the floor of the brooder and the danger of fires will thus be minimized.

It will be noted from an inspection of Fig. 2 that the supporting legs will be secured to their respective pipes so as to extend parallel to and underneath the pipe portions 21 and 23, overlapping each other somewhat and extending sufficiently on either side of the center line joining the axes of the pipes 16 and 19 to insure against tipping of the stove.

The upright 28 may be braced by means of a diagonal brace 31.

The hover 32 is supported upon the pipes

16 and 19, respectively. Where the stove is used as a brooder stove, as in Fig. 1, oil is fed to it through a feed pipe 60, the thermostatically controlled valve 61 and a pipe 62, which is tapped into the lower end of the air flue 19. (See Figs. 1 and 4.) Where the stove is used as a tank heater, the drip system is employed and I provide a readily attachable and detachable fuel tank, as shown in Fig. 5.

The fuel tank 34 has secured to its bottom a depending annular collar 35, to which are secured inwardly extending fingers 36, provided with hooks 37, adapted to hook over the edge of the pipe 19 in order to support the tank thereon in coaxial relation therewith. The collar 35 overlaps the upper end of the pipe 19 so as to guard against sudden drafts affecting the smooth flow of air currents therethrough.

The drip valve which is of an old construction is shown at 38. The fuel is allowed to drip from the valve 38 upon a mass of ashes 39 in the lower end of the air flue 19. This element is old and does not form a part of my invention. The oil is vaporized as it strikes against the ashes, which are heated by conduction of the heat from the portion of the stove where burning takes place through the walls of the stove.

Where the feed, shown in Fig. 1, is used, the oil works its way up through the mass of ashes by capillary action and is vaporized during the process. Combustion commences in the pipe 24 and continues through the pipes 23, 22, 21 and 20.

It may now be noted that the air within the sleeve 14 will be heated to a higher degree than the air surrounding the sleeve 14 and the general atmosphere within the brooder and consequently a column of air which is lighter than the remainder of the air within the brooder will be formed. This column of air will ascend, due to its levity and will create a forced draft within the brooder. Creation of this forced draft is accomplished by heat, which would otherwise go up the chimney in the form of waste heat.

The sleeve 14 serves not only to segregate a column of air for super-heating and forced draft but also serves to hold the heat within the brooder. Instead of having a direct avenue of escape through an opening in the roof, the heated air must enter the sleeve at its lower end in order to escape. Thus all of the heated air above the lower end of the sleeve is trapped. In actual operation the heated air and gases ascend to the upper region of the building and then travel downwardly around the sleeve 14, after having cooled slightly. A continuous circulation of air throughout the entire building is thus assured.

Some changes may be made in the construction and arrangement of the parts of my invention without departing from the real

spirit and purpose of my invention, and it is my intention to cover by my claims, any modified forms of structure or use of mechanical equivalents, which may be reasonably included within their scope.

5 I claim as my invention:

1. In an oil burning stove, a horizontal stove portion serving as a combustion chamber and as a heat radiator, a chimney and an inlet flue extending upwardly from the stove portion to form a continuous chamber beginning with the inlet flue and terminating with the chimney, and means for dripping liquid fuel through the inlet flue into the stove portion, the stove walls being imperforate from the bottom of the stove portion to such a height above the intersections of the stove portion and chimney and flue that an excess flow of fuel will fill the stove portion, cut off the circulation of air therethrough, and cause a flame within the stove to be extinguished before the fuel will overflow from the stove.

2. In an oil burning stove, a horizontal stove portion comprising an S-shaped tube, a chimney and inlet flue extending upwardly from the ends of the stove portion to form a continuous chamber, and means for dripping liquid fuel through the inlet flue and into the stove portion, the stove walls being imperforate from the bottom of the stove portion to such a height above the intersections of the stove portion and chimney and flue that an excess flow of fuel will fill the stove portion, cut off the circulation of air therethrough, and cause a flame within the stove to be extinguished, before the fuel will overflow from the stove.

3. In an oil burning stove, a horizontal stove portion serving as a combustion chamber and a heat radiator, a chimney and an inlet flue extending upwardly from the stove portion to form therewith a continuous chamber beginning with the inlet flue and terminating with the chimney, the heights of the chimney and flue being several times their respective diameters, and means for dripping liquid fuel through the inlet flue into the stove portion, the stove walls being imperforate from the bottom of the stove portion to a height above the intersection of the stove portion and chimney and flue several times the diameter of chimney or flue.

4. In an oil burning stove, a horizontal stove portion serving as a combustion chamber and heat radiator, a chimney and an inlet flue extending upwardly from the stove portion to form therewith a continuous chamber beginning with the inlet flue and terminating with the chimney, means for supplying liquid fuel to the stove portion, and supporting means adjustably secured to the stove, said supporting means including a pair of clamp devices embracing the chimney and inlet flue respectively, and adapted to be adjusted ver-

tically on said chimney and flue and to be secured thereto in any adjusted position.

5. In an oil burning stove, a horizontal stove portion comprising an S-shaped tube, a chimney and inlet flue extending upwardly from the ends thereof to form a continuous chamber, means for supplying liquid fuel to the stove portion, and a brace extending between and secured to the chimney and flue at a height from the stove portion, to form a rigid structure.

6. In an oil burning stove, a horizontal stove portion serving as a combustion chamber and heat radiator, a chimney and an inlet flue extending upwardly from the stove portion and forming therewith a continuous chamber beginning with the inlet flue and terminating with the chimney, means for supplying liquid fuel to the stove portion, supporting means adjustably secured to the stove, said supporting means including a pair of clamp devices embracing the chimney and inlet flue respectively, and adapted to be secured thereto in any of several vertically adjusted positions, and a brace extending between and secured to the chimney and flue at a height from the stove portion, to form a rigid structure wherein the support for the stove may be transmitted to the chimney and flue.

7. In an oil burning stove, a horizontal stove portion serving as a combustion chamber and as a heat radiator, a chimney and an inlet flue extending upwardly from opposite extremities of the stove portion to form a continuous chamber of which the regions above the stove portion are of such depth and so constricted as to support combustion only when there is an air passage through the stove portion and means for supplying liquid fuel to the stove portion, the stove walls being devoid of any opening to the outside atmosphere from the bottom of the stove portion to such a height thereabove that an excess flow of fuel will fill the stove portion, cut off the circulation of air thereto and cause the flame within the stove to be extinguished before the fuel can overflow from the stove.

8. In an oil burning stove, a horizontal stove portion comprising an S shaped tube serving as a combustion chamber and as a heat radiator, a chimney and an inlet flue extending upwardly from opposite extremities of the stove portion to form a continuous chamber of which the regions above the stove portion are of such depth and so constricted as to support combustion only when there is an air passage through the stove portion and means for supplying liquid fuel to the stove portion, the stove walls being devoid of any opening to the outside atmosphere from the bottom of the stove portion to such a height thereabove that an excess flow of

fuel will fill the stove portion, cut off the circulation of air thereto and cause the flame within the stove to be extinguished before the fuel can overflow from the stove.

⁵ Signed this 16th day of May, 1928, in the county of Woodbury, and State of Iowa.

CLAUDE SIEBRING.
